UNITED STATES PATENT OFFICE.

CHARLES A. CLINE, OF MARION, IOWA.

STOREROOM RACK.

Application filed June 19, 1924. Serial No. 721,060.

To all whom it may concern:

Be it known that I, CHARLES A. CLINE, a citizen of the United States, residing at Marion, in the county of Linn and State 5 of Iowa, have invented certain new and useful Improvements in Storeroom Racks, and do hereby declare the following to be a full, clear, and exact description of the invention, such as will enable others skilled in the art 10 to which it appertains to make and use the same.

This invention relates to storeroom racks of that kind used where supplies are kept including repair parts for the shops, etc., 15 and adapted to occupy such a position within a storeroom that both sides thereof will be accessible and comprising a main shelf and supplemental shelves arranged above and below the main shelf, a fixed platform 20 arranged in alinement with the main shelf, and a fixed platform arranged in alinement with the supplemental shelf next above the main shelf. Due to the fact that the shelves are closely related, the platforms prevent 25 easy access to the lower supplemental shelf and to the central portion of the main shelf, and this constitutes the sole known objection to the rack.

This invention has for its primary object 30 to overcome the stated objection to the rack, and to attain this end I so mount the platforms that they may be moved upwardly and inwardly when it is desired to gain access to the lower supplemental shelf and 35 to the central portion of the main shelf.

A further object of the invention is the provision of novel and simple means for releasably holding the platforms in raised 40 position.

With the above and other objects in view, the invention embodies the construction, combination and arrangement of parts hereinafter fully described and claimed, and illustrated in the accompanying drawings, 45 wherein:

Figure 1 is a view in side elevation of a storeroom rack embodying my invention,

Figure 2 is a sectional view taken on the horizontal plane indicated by the line 2—2 of Figure 1,

Figure 3 is a view in end elevation of the storeroom rack,

Figure 4 is a sectional view taken on the vertical plane indicated by the line 4—4 of Figure 1, and

Figure 5 is a detail sectional view on an

enlarged scale illustrating the manner in which the supplemental shelf platform is supported in raised position.

The rack comprises a plurality of pairs 60 of relatively spaced uprights 1. The uprights of each pair are connected together by cross pieces 2, 3, 4 and 5 upon which rest and to which are secured a lower supplemental shelf 6, a main shelf 7, and upper 65 supplemental shelves 8 and 9. The cross pieces 2 and 3 are longer than the other cross pieces and extend beyond the lateral edges of the shelves. These cross pieces are supported at their outer ends by short 70 uprights 10. The cross pieces 4 are longer than the cross pieces 5 and they project beyond the lateral edges of the shelf 8. The projecting ends of the cross pieces 3 form supports for the main platforms 11, and 75 the projecting ends of the cross pieces 4 form supports for the supplemental platforms 12. The platforms 11 and 12 prevent easy access to the shelf 6 and to the central portion of the shelf 7. The rack thus far 80 described is similar to the storeroom rack now in use in railway stations.

In accordance with the present invention, the supplemental platforms 12 are connected to the uprights 1 by hinges 13 in order 85 to permit them to be swung upwardly and inwardly when it is desired to gain access to the central portion of the main shelf 7. These platforms are adapted to be supported in raised position by spring catches 14 90 which are secured to the uprights 1 as shown at 15 in Figure 5. The main platforms 11 comprise inner and outer sections 16 and 17, respectively. These sections are united at 95 their inner lower corners by hinges 18, and the inner sections 17 are connected to the main shelf 7 by hinges 19, in order to permit the sections 17 to be swung upwardly against the uprights 1 and the outer sections 16 to be folded against the sections 17, 100 as shown in Figure 4, when it is desired to gain access to the lower shelf 6. The main platforms 11 are adapted to be held in their folded and raised position against casual movement by 105 springs 20 which are secured at 21 to the under side of the shelf 7 and which are connected at the outer platform section 16 as at 22. When the main platforms 11 are in raised and folded position, the free edges of 110 the platform sections 16 rest upon the cross pieces 3.

Figure 1 is a view in side elevation of a storeroom rack embodying my invention, Figure 2 is a sectional view taken on the horizontal plane indicated by the line 2—2 of Figure 1, Figure 3 is a view in end elevation of the storeroom rack, Figure 4 is a sectional view taken on the vertical plane indicated by the line 4—4 of Figure 1, and Figure 5 is a detail sectional view on an

- As the platforms 11 and 12 may be readily raised, and due to the fact that the spring latches 14 and the springs 20, are adapted to automatically function to hold the platforms in raised position immediately after they have been moved into such position, it should be apparent that access may be readily gained to the lower supplemental shelf 6 and to the central portion of the main shelf 7.
- It should be understood that the drawings are merely illustrative and do not pretend to give exact proportions. Furthermore, the said drawings are illustrative of a preferred construction, it being my expectation that various changes and modifications may be made without departing from the spirit and scope of the invention.
- What is claimed is:
1. A rack of the character set forth, comprising a shelf, a sectional platform, a hinge connecting the inner edges of the platform sections, a hinge connecting the inner platform section to the shelf, means adapted to support the platform sections in extended position in the plane of the shelf, and spring means adapted to support the platform sections folded one against the other at an angle to the shelf.
2. A rack of the character set forth, comprising a shelf, a sectional platform at each side edge of the shelf, a hinge connecting the inner edges of the sections of each platform to permit the sections to be extended in the plane of the shelf and folded and arranged in a position at right angles to the shelf, hinges connecting the inner platform sections to the side edges of the shelf, means adapted to support the platform sections in extended and folded positions, and a spring positioned beneath the shelf and secured at its ends to the outer section of each platform.

In testimony whereof I affix my signature in presence of two witnesses.

CHARLES A. CLINE.
